(57) **CLAIM**

The ornamental design for a cleaning plate for an electric mop, as shown and described.

DESCRIPTION

FIG. 1 is a front perspective view of a cleaning plate for an electric mop in accordance with my design;

FIG. 2 is a front side view thereof;

FIG. 3 is rear side view thereof;

FIG. 4 is a left side view thereof;

FIG. 5 is a right side view thereof;

FIG. 6 is a top view thereof;

FIG. 7 is a bottom view thereof;

FIG. 8 is an enlarged view of a circle portion 8 of FIG. 1; and,

FIG. 9 is an enlarged view of a circle portion 9 of FIG. 1. The broken lines depict portions of the cleaning plate for an electric mop that form no part of the claimed design.

1 Claim, 9 Drawing Sheets
